Patented June 20, 1916.

INVENTOR

Walter C. Beckwith,
By Owen Owen & Crampton,
His atty.

UNITED STATES PATENT OFFICE.

WALTER C. BECKWITH, OF FOSTORIA, OHIO.

RAILROAD-TORPEDO.

1,187,486.

Specification of Letters Patent. Patented June 20, 1916.

Application filed September 30, 1915. Serial No. 53,416.

To all whom it may concern:

Be it known that I, WALTER C. BECKWITH, a citizen of the United States, and a resident of Fostoria, in the county of Seneca and 5 State of Ohio, have invented a certain new and useful Railroad-Torpedo; and I do hereby declare the following to be a full, clear, and exact description of the invention, such as will enable others skilled in the 10 art to which it appertains to make and use the same, reference being had to the accompanying drawings, and to the characters of reference marked thereon, which form a part of this specification.

15 This invention relates to railroad torpedoes, and particularly to torpedoes commonly known as the 1904 fiber top or non-flying open-end-tube type.

The object of my invention is the 20 provision of an improved fiber torpedo of the class described, which is simple, durable and water-proof in its construction and easy and inexpensive to manufacture, whereby to enhance the practicability and commercial 25 value of torpedoes of this character.

The invention is fully described in the following specification, and while, in its broader aspect, it is capable of embodiment in numerous forms, a preferred embodiment 30 thereof is illustrated in the accompanying drawings, in which,—

Figure 1 is a perspective view of a torpedo embodying the invention attached to a rail. Figs. 2 and 3 are cross and longitudinal 35 sections, respectively, thereof, with portions of the rail engaging strap broken away, and Fig. 4 is a perspective bottom view of the torpedo with the ends of the strap broken away.

40 Referring to the drawings, 1 designates the explosive containing case, 2 the rail engaging strap, and 3 the base member, which latter serves both to close the ends of the case 1 and to carry the strap 2.

45 The case 1 comprises a short tubular section, preferably of strong paper, or other suitable fibrous material, and such section is flattened, as shown. The base member 3, which is also preferably composed of strong

50 paper or other suitable fibrous material, is substantially the same in width as the case 1 in its flattened form, and is of a length which is greater than the length of the case, to permit each end of the base member to 55 be doubled over the respective end of the

case. The member 3 is provided, in the present instance, centrally of its ends, with a pair of transversely spaced openings 4 through which the rail engaging strap 2 is successively threaded first in one and then 60 the other direction, whereby the strap is centrally retained to the base member as indicated, or in a similar manner. The strap 2 is preferably of lead or a similar pliant material to facilitate a threading of the 65 same through the openings 4, but may be of other material if desired and secured to the base member in any other suitable manner without departing from the spirit of the invention.

70 When the explosive 5, which is preferably of tablet form, has been inserted into the case 1 through one of the open ends thereof, the case is placed over a base member 3 having a strap 2 attached thereto, and the ends 75 of the base member are drawn closely over the open ends of the tube in closing relation thereto and secured in such position by a stitching 6 extending across the respective 80 ends of the torpedo, or in any other suitable 85 manner. The stitching 6, which is preferably employed to secure the base member to the case, extends entirely through the base member at the doubled over portion thereof and also through the interposed case end, 90 whereby the stitching, in addition to serving 95 to securely fasten the base member to the case, also closes the ends of the case. The securing of the fiber base member 3 to the case in this or a similar manner not only 95 renders torpedoes of this class safer to use, as the metal base member or clip commonly used in such torpedoes is omitted, but also provides a more effective closure for the ends 100 of the case than is possible by the use of the metal or base clips heretofore used.

I wish it understood that my invention is not limited to any specific construction, arrangement or form of the parts, as it is capable of numerous modifications without departing from the spirit of the claims.

Having thus described my invention, what I claim as new, and desire to secure by Letters Patent, is,—

1. In a railroad torpedo, an explosive containing case having open ends, a base member having its ends doubled over the open ends of said case, means extending through the doubled over ends of the base member and the interposed ends of the case to close 110

the case ends and to secure the base member thereto, and rail engaging means carried by said base member.

2. In a railroad torpedo, an explosive containing case, a strap-carrying fibrous base member having its ends doubled over the case ends, and means extending entirely through the doubled over ends of the base member and of the case to close the ends of 10 the case and to secure the base member thereto.

3. In a railroad torpedo, an explosive containing case, a strap carrying base member for said case having its ends doubled over 15 the case ends, and a stitching extending through the doubled over ends of the base member and through the interposed ends

of the case to close said case ends and to secure the base member thereto.

4. In a railroad torpedo, an explosive containing case of flattened tubular form composed of fibrous material, a fibrous base member for said case extending lengthwise thereof and having its ends doubled over the case ends, a stitching extending through the doubled over ends of the base member and through the interposed end portions of the case to close the latter and to secure the base member thereto, and a rail engaging member carried by said base member. 20 25 30

In testimony whereof, I have hereunto signed my name to this specification.

WALTER C. BECKWITH.
